[57] **CLAIM**

The ornamental design for a fence for an extension table or the like, as shown and described.

DESCRIPTION

FIG. 1 is a perspective view of a fence for an extension table or the like showing my new design;
FIG. 2 is a front elevational view thereof;
FIG. 3 is a rear elevational view thereof;
FIG. 4 is a top plan view thereof;
FIG. 5 is a bottom plan view thereof.

FIG. 6 is an enlarged left side elevational view; and
FIG. 7 is an enlarged right side elevational view thereof.
